UNITED STATES PATENT OFFICE.

HARRY E. McCANDLESS, OF ROCHESTER, NEW YORK, ASSIGNOR TO KENNEDY-McCANDLESS CORPORATION, OF ROCHESTER, NEW YORK, A CORPORATION OF NEW YORK.

COVER FOR NURSERY-CHAIR SEATS.

Application filed October 7, 1927. Serial No. 224,727.

This invention relates to a cover for the seat of a nursery chair, and has for its principal object to provide a more practical and efficient cover than any heretofore known.

5 Another object of the invention is to so design a cover that it will be entirely out of the way when moved to ineffective position.

It is a further object of the invention to provide a cover which may be moved easily 10 and quickly, from effective to ineffective position or vice versa.

With these and other ends in view, the invention comprises the structure and combination of parts which will appear more 15 clearly from the following description when read in conjunction with the accompanying drawings, the novel features being pointed out in the claims following the description.

In the drawings:

20 Figure 1 is a side elevation of a nursery chair showing one possible embodiment of the invention applied thereto;

Figure 2 is a rear elevation of the same, with the cover in its effective position;

25 Figure 3 is a fragmentary rear elevation of the same with the cover moved to its ineffective position;

Figure 4 is a fragmentary side elevation, showing the cover in its ineffective position;

30 Figure 5 is a plan of the chair seat and cover, and

Figure 6 is a vertical section taken approximately on the center line of the chair.

There is illustrated in the drawing a nursery chair of conventional form including 35 upright members 11 and 12 which form the legs of the chair and to which is attached a seat member 13. The members 11 and 12 may be extended upwardly so as to provide 40 for a back and arms on the chair if desired.

Various forms of covers have been suggested heretofore to cover the seat of the chair when it is not in use. The style of cover commonly used has been hinged at 45 its rear edge and has been moved to ineffective position by having its front edge swung upwardly. This construction has a great disadvantage in that the cover, even when swung upwardly, is not entirely out of the 50 way, but obstructs to some extent the rear portion of the seat. Furthermore, this cover, when in ineffective position, comes between the back of the chair and the child sitting thereon, and is less comfortable for the child 55 to lean against than the back itself would be.

In the present construction, these disadvantages are obviated by the provision of a cover which, when moved to ineffective position, is entirely removed from the seat of the chair and in no way obstructs any portion 60 thereof or prevents the child from leaning against the back of the chair.

As one possible embodiment of an improved cover having these desirable characteristics, there is shown in the drawings 65 a cover member 14, which may be in the nature of a flat piece of material, the dimensions of this member being sufficient so that it may cover the desired portion of the seat, as shown especially in Figures 5 and 6. This 70 cover is provided with novel mechanism which keeps it from becoming separated from the chair and yet permits it to be removed entirely from the top surface of the 75 seat.

Such attaching mechanism may consist, for example, of the guiding members 15 attached to the cover and the cooperating guiding or control member 16 attached to the seat structure. The members 15, as 80 shown particularly in Figure 5, extend along the sides of the cover, spaced a short distance therefrom, and these guiding members continue somewhat past the rear edge of the cover to a position just behind the rear edge 85 of the seat structure, where they are then bent at right angles and attached to the cover as clearly indicated in Figure 5. These guiding members 15 may be formed of rods or stiff wires or in any other suitable way. 90

The cooperating control or guide member 16 above mentioned may be, for example, of the shape best shown in Figure 2. It consists of a rod or wire the greater portion 95 of which is straight but which has two U-shaped offsets or loops 17 formed therein. The straight portion of the member 16 between the two loops is placed slightly below the plane of the top surface of the seat, as may be seen from Figures 2 and 6, and the 100 loop portions 17 pass between the guiding members 15 and the edges of the cover and loosely embrace these guiding members, as indicated especially in Figure 2. This control or guiding member 16 may be pivotally secured to the chair in any suitable manner. For instance, the ends of the member may be mounted in bearings 18 which will prevent longitudinal movement but allow rotary 105 movement of the member, these bearings 18 110

being attached, in turn, to the legs 12 of the chair. These legs are fixed relative to the seat 13 of the chair, and the guiding member 16 may therefore be said to be mounted on the seat structure of the chair, this term "seat structure" being intended to include the seat itself or any parts attached thereto, as distinguished from the cover which is movable relative to the seat and attached parts.

The operation of the improved cover herein disclosed is exceedingly simple. The position shown in Figures 1, 2, 5 and 6 indicates the cover in its effective position, covering the seat. When it is desired to move the cover to ineffective position, it is slid rearwardly over the seat, the guiding members 15 on the cover meanwhile sliding through the loops 17. When the cover has reached the rearward limit of its motion, the rear edge thereof may then be swung downwardly until the cover hangs vertically at the back of the chair, as illustrated in Figures 3 and 4. During this swinging movement, when the cover is oscillated from the plane of the seat into a vertical plane, the guiding member 16 rotates through approximately 90°, so that the loops 17, which were formerly vertical, now lie horizontally, as in Figure 4. In this ineffective position, the bent portions at the forward ends of the guiding members 15 on the cover come in contact with the loops 17 and prevent further downward movement of the cover, thus supporting it so that the bottom thereof is clear of the floor.

When it is desired to replace the cover, the lower edge thereof is grasped and the cover is swung upwardly until it lies approximately horizontal or in the plane of the seat. It is then shoved forwardly, sliding over the surface of the seat, until it resumes its effective position. When in this position, the bent portions at the rear ends of the guiding members 15 come in contact with the loops 17 and prevent further forward movement of the cover, thus acting as stop means to locate the cover in proper position. This action is indicated particularly in Figures 5 and 6.

It will now be seen that a novel cover has been designed which, when in its ineffective position, is entirely removed from the surface of the seat and is as completely out of the way as though it had been severed from the chair and removed to a distance. Furthermore, it is apparent that the cover is simple in operation and may be quickly moved to ineffective position or replaced.

While one embodiment of the invention has been disclosed, it is to be understood that the inventive idea may be carried out in a number of ways. This application is therefore not to be limited to the precise details shown, but it intended to cover all modifications thereof falling within the spirit of the invention or the scope of the appended claims.

I claim:

1. The combination with a seat structure of a nursery chair, of a cover member, guiding members extending parallel to each of two edges of said cover member and spaced therefrom, said guiding members being extended past one end of said cover member, and a guiding member pivotally secured to said seat structure, said last named guiding member extending substantially perpendicular to the guiding members on the cover and including a plurality of loop portions through which said first named guiding members pass.

2. The combination with a seat structure of a nursery chair, of a cover member, guide rods spaced from the side edges of the cover member in parallel relationship thereto and having right-angled end portions extending toward and attached to the cover member, and guiding means on the seat structure cooperating with the aforesaid guide rods on the cover member.

3. The combination with a seat structure of a nursery chair, of a cover member, and cooperating guide rods on both the cover member and seat structure for connecting said parts by a relatively slidably movement.

In witness whereof, I have hereunto signed my name.

HARRY E. McCANDLESS.
